[57] **CLAIM**

The ornamental design for a combined toy drum and drum stick, as shown and described.

DESCRIPTION

FIG. 1 is a perspective view of the top, front and one side of a combined toy drum and drum stick showing our new design;

FIG. 2 is a front elevational view thereof;

FIG. 3 is a side elevational view of said one side;

FIG. 4 is a rear elevational view thereof;

FIG. 5 is a side elevational view of the opposite side thereof;

FIG. 6 is a top plan view thereof;

FIG. 7 is a bottom plan view thereof; and

FIG. 8 is a perspective view similar to FIG. 1 with the drum stick detached from the toy drum.

FIG. 1

FIG. 2

FIG. 3

FIG. 4

FIG. 5

FIG. 6

FIG. 7
